UNITED STATES PATENT OFFICE.

WILHELM SCHEERER, OF TUTTLINGER, GERMANY.

DESIGN FOR A HANDLE FOR SURGICAL INSTRUMENTS.

SPECIFICATION forming part of Design No. 22,134, dated January 17, 1893.

Application filed September 15, 1892. Serial No. 446,110. Term of patent 7 years.

To all whom it may concern:

Be it known that I, WILHELM SCHEERER, of Tuttlinger, in the Kingdom of Würtemberg, Germany, have invented and produced a new and original Design for a Handle for Surgical Instruments, Knives, and the Like, of which the following is a specification, reference being had to the accompanying drawings, forming part thereof.

Figures 1 and 2 are front and side views respectively of a handle made according to my design.

The design consists in a handle for surgical instruments, knives, and the like, made with a curved depression transversely across the upper portion of each of its broad sides, *i. e.* at that part thereof which is adjacent to

the blade or instrument, the depression on each side being diametrically opposite.

On the accompanying drawings *a, a*, are the 25 curved depressions. The remainder of the handle is of the usual shape, the one shown in the drawings being fish-tail, longitudinally grooved, and with beveled edges.

What I claim is:—

The design for a handle for surgical instruments, knives, and the like, herein described.

In testimony whereof I have signed this specification in the presence of two subscribing witnesses.

WILHELM SCHEERER.
